Application February 5, 1937, Serial No. 67,458

Term of patent 14 years

To all whom it may concern:

Be it known that I, James S. Steelman, a citizen of the United States, residing at Millville, Cumberland County, New Jersey, have invented a new, original, and ornamental Design for a Bottle, of which the following is a specification, reference being had to the accompanying drawing, forming part thereof, wherein:

Figure 1 is a front view;

Figure 2 is a rear view; and

Figure 3 is a top view of a bottle showing my new design.

The characteristic features of my new design reside in application of a grape and grape leaf motif to a bottle, the body portion of the bottle depicting bunches of grapes alternating with grape leaves arranged in vertical rows separated by vertical bars, the shoulder portion of the bottle being draped with bunches of grapes and grape leaves.

I claim:

The ornamental design for a bottle as shown and described.
